UNITED STATES PATENT OFFICE.

SAMUEL J. WENTWORTH, OF NEWPORT, KENTUCKY, ASSIGNOR TO UNITED SHOE MACHINERY COMPANY, OF PATERSON, NEW JERSEY, A CORPORATION OF NEW JERSEY.

WELT-BUTT-TACKING MACHINE.

1,195,304.

Specification of Letters Patent. Patented Aug. 22, 1916.

Application filed May 1, 1913. Serial No. 764,832.

To all whom it may concern:

Be it known that I, SAMUEL J. WENTWORTH, a citizen of the United States, residing at Newport, in the county of Campbell 5 and State of Kentucky, have invented certain Improvements in Welt-Butt-Tacking Machines, of which the following description, in connection with the accompanying drawings, is a specification, like reference 10 characters on the drawings indicating like parts in the several figures.

This invention relates to shoe making machines and is herein shown as embodied in a machine for tightening uppers of lasted 15 shoes at the butt ends of the welt, positioning the welt ends and fastening the upper, or the upper and the welt ends, which machine possesses certain features of novelty that are advantageous.

20 One feature of the invention consists in the combination with upper tightening devices for engaging in the welt crease on the two sides of a shoe which are manually separated for the introduction of the shoe between them and are automatically closed to effect the upper tightening operation of means to guide the operator in presenting the shoe with its welt crease in the plane of approach of the said devices.

25 Preferably the machine is arranged to allow lateral vibration of the shoe angularly between the tightening devices to work the upper into tightened position for fastening.

In accordance with another feature of the 30 invention power driven tackers are suspended above the shoe and are connected with the tighteners for movement by the latter into position to fasten the upper, the tackers being arranged to be set in operation by the workman, after he has tightened the upper by the use of the tighteners, fasten the welt ends in the positions to which they are moved by the crease engaging devices.

35 The shoe is shown as yieldingly upheld by a spindle having a last pin and mounted to slide lengthwise of the shoe in a carriage over a preferably stationary track. In accordance with another feature of the invention the spindle is raised to thrust the last 40 up against the crease engaging blades which constitute the upper tightening devices. By this means the upper and the feather of the innersole between the blades and the last bottom are compressed. If the described 45 tackers are used the welt and the between

substance of the inseam is also compressed between the tackers and the last bottom, all preparatory to the insertion of the fastenings and to the clinching of the fastenings upon the metallic heel plate of the last under 50 conditions to render them most effective.

In accordance with a further feature of the invention the last spindle is operatively connected with the upper tightening devices for movement vertically when said devices 55 are moved horizontally. In the illustrated embodiment of this feature of the invention, the last spindle is depressed when the upper tightening devices are opened, whereby to facilitate the removal of a shoe which has 60 been operated upon. Also said last spindle is raised when the upper tightening devices are closed, so that lifting of the stock from the last bottom by the tightening devices is avoided and the last is caused to compress 65 the stock against the under face of the tacker preliminarily to the insertion of the fastening tacks. In the illustrated embodiment of the invention the last spindle rests upon a horizontal arm of an angle lever which is 70 spring actuated in the direction to uplift the last and the said horizontal arm is connected to the treadle by which the tightening devices are opened. An advantageous feature 75 of this construction is that there exists between the lifting spring and the last connections sufficient mass to absorb the blow of the tackers and hold the shoe substantially 80 rigid for the tacking operation.

85 A further feature of the invention involves a new use of two pronged tacks or staples in this relation and comprises mechanism for inserting such staples to fasten the tightened upper and also the positioned 90 welt and counter ends to one another and to the innersole. Heretofore a single pronged headed tack has been driven through the welt and into the underlying feather of the innersole. There are obvious 95 advantages in driving the fastening into the relatively thick body portion of the innersole instead of into the feather. Accordingly in the machine herein shown the tackers are arranged to drive the staples so that they will bridge or straddle the between 100 substance of the inseam, one leg or prong going into the welt and the other into the body of the innersole. Advantageously for the described use, the staple is specially 105 formed, in accordance with a feature of this 110

invention, to present a head shaped to the contour of the portion of the work bridged by it and preferably also to present legs of suitable relative lengths for the thickness of stock into which they are to be driven and under which they may be clenched.

As shown, the machine is constructed and arranged to impart to the staple the required shape and the staple driver is specifically formed to drive such a staple. The driver will shape the head of the staple in the operation of driving it if the staple is not preliminarily shaped.

These and other features of the invention will appear more clearly from the following description taken in connection with the accompanying drawings of a preferred embodiment of the invention and will then be pointed out in the claims.

Figure 1 is a side elevation of a preferred embodiment of the invention; Fig. 2 is a front elevation, the shoe being shown in section; Fig. 3 is a perspective view of the upper tightening devices; Fig. 4 is a perspective view of a strip of staple material and shows staples in successive steps of formation; Fig. 5 is a perspective view of a lasted welt shoe after the upper has been tightened and the welt butts positioned by this machine and said parts secured by staples driven in accordance with this invention.

The column of the machine supports a driver cam shaft bearing also a fast clutch member and a coöperating clutch member which is also a loose pulley and there is provided treadle controlled means for closing the clutch and automatic means for opening the clutch and stopping the machine at the end of one cycle of the machine's power operation. These parts of the machine are similar to those of the power assembling machine shown in United States Letters Patent No. 1,023,794 granted April 23, 1912, on application of Orrell Ashton, and it is not necessary to describe them here.

From the front side of the machine column projects a bracket 2 upon which a carriage 4 slides in a direction lengthwise of the shoe for movement of the shoe into and out of position to be operated upon. A spindle 5 is movable vertically through the carriage, is provided with a last pin on its upper end and is normally upheld by a light spring 6 located within the carriage. Upward pressure of a substantial character is effected by a lever 8 pivoted at 9, the horizontal arm of the lever underlying the lower end of the spindle while a vertical arm of the lever is acted upon by a stiff spring 10.

Upper tightening devices are pivotally mounted upon opposite lateral sides of the column and comprise angle levers 15 pivoted on bolts 16 and arranged with their rear arms crossed as in Fig. 3. The front

arms of the levers 15 are slotted lengthwise to receive the stems of upper tightening blades 18 which are fixed in adjusted position lengthwise of the shoe for long and short shoes by nuts 19. The levers 15 are actuated in a direction to move the blades 18 inwardly against a shoe for performing their upper tightening function by strong springs 20 which encircle the bolts 16. Reverse movement of the levers 15 is effected by the engagement of the rear crossed arms of said levers by the upper end 25 of a bell crank lever, Fig. 1, which is pivoted to the machine column and from the horizontal arm of which a treadle rod 26 extends downwardly.

A spring 28 is arranged between a collar on the treadle rod and the upper face of lever 8 and through this spring the treadle rod depresses the horizontal arm of lever 8 to relieve upward pressure upon the shoe spindle 5 at the same time that the closing pressure on the upper tightening blades 18 is relieved whereby the movement of a shoe into or out of position between said blades is facilitated. A back stop 29 is adjustably supported in the column as shown in Fig. 1.

Tacking mechanisms are pivotally suspended from the frame of the machine above the shoe by universal joints 30 and 31 have suitable jointed connections 32 with the levers 15 by which said tack driving mechanisms are moved in and out over the shoe bottom and are positioned by the upper tightening devices properly for fastening the upper, and preferably also the welt and counter ends, in the positions to which the stock is manipulated by the tightening devices. The tacking mechanisms comprise drivers 35, the heads of the two drivers being located under the opposite ends of a block 36 pivoted on the front end of the driver lever 38. The drivers extend downwardly through the ball joints 30 and carry collars 34 against which act the driver lifting springs 37. The lower portions of the drivers extend through tack presenting means by which tacks are supplied in position to be inserted.

As herein shown the tacks are double pointed fastening devices or staples and the presenting means is arranged to deliver these staples under the drivers in position for the heads of the staples to extend across the inseam adjacent to the tightening devices 18 where one staple leg will be driven through the welt, upper and counter into the feather of the innersole at the outer side of the channel lip and the other leg of the staple will be driven into the body portion of the innersole at the inner side of the channel lip.

The staple material for each tacking mechanism, in the form shown in Fig. 4, is supplied through a guide 40 by which it is

directed into a forming block 42 along which it is fed by the pawl 44 actuated by a cam face on a leg 45 depending from the collar 34 on the driver 35. The lower end of the leg 45 is equipped with staple forming projections 46 which coöperate with the walls of suitably formed recesses in the shaping block 42 for bending the staple material into the desired form. Preferably 10 this form of staple will comprise a head or bridge one end portion of which lies in a lower plane than the other end portion to adapt said staple head to fit over the inseam material and down upon the body of the 15 innersole as shown in Fig. 5. The inner and outer legs of the staple will be suitably proportioned, preferably, so that as the staple is pressed into engagement with the work by the driver the inner leg will engage 20 the body of the innersole at about the same time that the outer leg engages the welt which, as is well understood, will lie in a higher plane than the body of the innersole. For these purposes the forming tools are 25 preferably constructed and arranged to shape the staple material substantially as shown in Fig. 4 to produce a staple one leg of which is longer than the other and the head or bridge of which is bent to lie in a 30 lower plane at the end adjacent to the inner leg than at the end adjacent to the outer leg. The staple engaging face of the driver 35 is also preferably formed with the portion that engages over the end of the inner 35 leg of the staple in a lower plane than the portion which engages over the outer leg of the staple. When a driver thus formed descends upon the work it approximately fits the cross sectional contour of the work at 40 the staple receiving points so that both legs of the staple are driven firmly. Such a driver might be relied upon alone to bend the head of the staple into appropriate form to fit the contour of the work. The staple 45 may advantageously be so formed or the driver so shaped as to cause the outer staple leg to slant inwardly.

In the use of the machine the operator will depress the treadle to which the rod 26 50 is connected and thereby separate the upper tightening blades 18 and relieve the upward pressure upon the last spindle 5. Having then placed a lasted shoe with the last in it, upon the spindle he will slide the shoe 55 and the carriage 4 backwardly into the machine until the shoe engages the back stop 29. He will then relieve the pressure upon the treadle and allow the springs 20 to close the upper tightening devices. The operator 60 is enabled by means of the treadle to control the closing of the tightening devices and by his hands upon the shoe to insure that said devices enter the welt crease properly and without injury to the shoe. He 65 may also turn the shoe slightly from side to side to facilitate the seating of the blades 18 in the welt crease and their tightening and contracting action on the stock. If desired, manual means might be applied for forcing the blades in the direction for tightening the stock but I consider that the springs 20 may be of such strength as to be adequate for this purpose. The upward pressure of the last spindle, effected by the spring 10, presses and holds the shoe firmly 70 up against the lower face of the blades 18 after the treadle is released. This is important because thereby any tendency which the upper tightening operation might have to lift the stock from the last bottom is 75 overcome or prevented and the shoe is upheld firmly for the tack driving operation. The double pointed tacks are inserted by the power driven mechanism in response to the closing of the clutch which is effected 80 by a suitable treadle, the upper tightening devices having properly positioned the tackers for the insertion of the staples where they will extend across the same as shown in Fig. 5. The feeding and shaping of the 85 staples is effected progressively during the successive operations of the tacker. When the shoe has been tacked the treadle rod 26 is again depressed to facilitate the removal of the shoe and the insertion of the next one. 90

It will be understood that with these novel mechanisms for tightening and fastening the shoe stock of a lasted shoe having a welt crease there may be used mechanism suitably incorporated in the machine for 95 skiving the welt ends.

Having explained the nature of this invention and described a preferred construction embodying the same, I claim as new and desire to secure by Letters Patent of the 100 United States:

1. A machine of the class described having, in combination, upper tightening devices to engage opposite sides of a lasted shoe in the welt crease, actuating means normally forcing said devices into upper tightening position, manual means for overcoming the force of said actuating means and separating said devices while a shoe is inserted and governing the approach of said 105 devices into upper tightening relation to the shoe and means additional to said devices for guiding the operator in presenting the shoe with its welt crease in the plane of approach of said devices. 110

2. A machine of the class described having, in combination, upper tightening devices to engage opposite sides of a welted shoe in the welt crease, actuating means normally forcing said devices into upper tightening position, manual means for overcoming the force of said actuating means and separating said devices while a shoe is inserted and governing the approach of said 115 devices into upper tightening relation to the shoe and means additional to said devices for guiding the operator in presenting the shoe with its welt crease in the plane of approach of said devices. 120

3. A machine of the class described having, in combination, upper tightening devices to engage opposite sides of a welted shoe in the welt crease, actuating means normally forcing said devices into upper tightening position, manual means for overcoming the force of said actuating means and separating said devices while a shoe is inserted and governing the approach of said 125 devices into upper tightening relation to the shoe and means additional to said devices for guiding the operator in presenting the shoe with its welt crease in the plane of approach of said devices. 130

- shoe and means additional to said devices for guiding the operator in presenting the shoe with its welt crease in the plane of approach of said devices, said machine being 5 constructed and arranged to permit the shoe to be laterally vibrated angularly while the tightening devices are pressing it to produce increased tightening effect.
3. A machine of the class described having, in combination, upper tightening arms bearing welt crease engaging blades and movable about axes substantially perpendicular to the plane of the shoe bottom, extensions formed on said arms in the rear of 10 said axes, yielding means normally holding the arms with the blades in upper tightening relation, and an actuator arranged to contact with said extensions and to be operated by bodily force of the workman to 15 move said arms reversely for the introduction of the shoe between said blades and to control the movement of said blades into crease engaging position, substantially as described.
- 20 4. A machine of the class described having, in combination, upper tightening devices to engage opposite sides of a lasted shoe in the welt crease, a back stop for the shoe, carrier levers for swinging said devices inwardly together toward the shoe 25 positioned against said back stop, and means for holding said devices in different positions of adjustment on said carriers to adapt them for different lengths of shoes.
- 30 5. A machine of the class described having, in combination, upper tightening devices to engage opposite sides of a welted shoe in the welt crease, actuating means normally forcing said devices into upper 35 tightening position, manual means for overcoming the force of said actuating means and separating said devices while a shoe is inserted and governing the approach of said devices into upper tightening relation to the 40 shoe, tackers suspended from above the shoe in fixed relation to the tightening devices laterally of the shoe and moved into positions over the shoe welt by the upper tightening devices and power driving mechanism 45 for said tackers arranged to be set into operation by the workman after he has tightened the upper by the use of said devices.
- 50 6. A machine of the class described having, in combination, upper tightening devices to engage opposite sides of a lasted shoe in the welt crease, and devices arranged relatively thereto to position staples at each 55 side of the shoe across the inseam and to insert said staples with one leg through the upper at the outer side of the innersole channel lip and the other leg into the body of the innersole at the inner side of the channel lip.
- 60 7. A machine of the class described having, in combination, upper tightening devices to engage opposite sides of a welted 65 shoe in the welt crease, and power driven mechanisms positioned by said upper tightening devices to locate staples where they will extend across the inseam at each side of the shoe and operated to insert said staples. 70
8. A machine of the class described having, in combination, upper tightening devices to engage opposite sides of a lasted shoe in the welt crease, and power driven mechanisms positioned by said upper tightening devices to locate staples where they will extend across the inseam at each side of the shoe and operated to drive said staples into positions where one portion of the head of each staple will lie substantially in the 75 plane of the top of the inseam and another portion will lie in substantially the plane of the body of the innersole.
9. A machine of the class described having, in combination, upper tightening devices to engage opposite sides of a lasted shoe in the welt crease, and power driven mechanisms positioned by said upper tightening devices to locate staples where they will extend across the inseam at each side of the shoe and operated to insert said staples, 80 said mechanism comprising driver bars the lower end faces of which are contoured to fit across the inseam and rest down upon the body of the innersole at the inner side 85 of the inseam.
10. A machine of the class described having, in combination, upper tightening devices to engage opposite sides of a lasted shoe in the welt crease, and power driven mechanisms positioned by said upper tightening devices to locate staples where they will extend across the inseam at each side of the shoe, and including means for feeding 90 the staples and for driving them having 95 provisions for forming portions of the heads of the staples into two planes to enable them to fit the contour of the portions of the above mentioned shoe into which they are driven.
11. A machine of the class described having, in combination, upper tightening devices to engage opposite sides of a welted shoe in the welt crease, and power driven mechanisms to insert staples across the inseam with one leg going through the welt, 100 upper and counter into the feather of the innersole on the outer side of the channel lip and the other going into the body of the innersole on the inner side of the channel 105 lip, and staple presenting means operating 110 to shape the staples so that the points of the inner and the outer legs will evenly engage the respective surfaces to which they are presented.
12. A machine of the class described having, in combination, upper tightening devices to engage opposite sides of a lasted shoe in the welt crease, power driven mechanisms to insert staples across the inseam with one 115 leg going through the welt, upper and coun- 120
- 130

- ter into the feather of the innersole on the outer side of the channel lip and the other going into the body of the innersole on the inner side of the channel lip, and staple presenting means operating to shape the staples so that the portion of the staple head which is to extend inwardly from the channel lip shall lie in an appropriately lower plane than the portion of the head which is to 10 overlie the inseam.
13. A machine of the class described having, in combination, an upper tightening device adapted to engage a welted shoe in the welt crease near the butt end of the welt for 15 forcing the shoe stock into position to be secured, and mechanism arranged to operate in relation to said device to present a staple so that it will extend across the inseam and to drive the staple with one leg going 20 through the upper and welt into the feather of the innersole on the outer side of the channel lip and the other leg going into the body of the innersole at the inner side of the channel lip.
14. A machine of the class described having, in combination, an upper tightening device adapted to engage a lasted shoe in the welt crease near the butt end of the welt for 25 forcing the shoe stock into position to be secured, and mechanism arranged to operate in relation to said device to present a staple so that it will extend across the inseam with the portion of its head which is directly above the inseam in a higher plane than 30 the portion of its head which is nearer the middle of the shoe and to drive the staple with one leg going through the upper and welt into the feather of the innersole on the outer side of the channel lip and the other 35 leg going into the body of the innersole at the inner side of the channel lip.
15. A machine of the class described having, in combination, an upper tightening device adapted to engage a lasted shoe in the 40 welt crease near the butt end of the welt for forcing the shoe stock into position to be secured, and mechanism arranged to operate in relation to said device to present a staple so that it will extend across the inseam and 45 to drive the staple with one leg going through the upper and welt into the feather of the innersole on the outer side of the channel lip and the other leg going into the body of the innersole at the inner side of the 50 channel lip, said staple presenting and driving mechanism operating to bend one portion of the head of the staple into a lower plane than another portion and to position the staple across the inseam adjacent to said 55 tightening device with the higher portion of the staple head directly above the inseam.
16. A machine of the class described having, in combination, upper tightening devices to engage opposite sides of a lasted 60 shoe in the welt crease, actuating means normally forcing said devices into upper tightening position, manual means for overcoming the force of said actuating means to allow said devices to separate for the introduction and removal of a shoe, a vertically 65 movable support for the shoe, a spring for upwardly pressing said support, and connections from said manual means through which the upward pressure is relieved when the closing pressure on the tightening devices is relieved.
17. A machine of the class described having, in combination, upper tightening devices to engage opposite sides of a lasted shoe in the welt crease, actuating means normally forcing said devices into upper tightening position, manual means for overcoming the force of said actuating means to allow said devices to separate for the introduction and removal of a shoe, a vertically 70 movable support for the shoe, a lever for raising said support, lifting means acting through said lever, and connections from said manual means to the lever for relieving the lifting pressure on the shoe support.
18. A machine of the class described having, in combination, upper tightening devices to engage opposite sides of a lasted shoe in the welt crease, actuating means normally forcing said devices into upper tightening position, manual means for overcoming the force of said actuating means to allow said devices to separate for the introduction and removal of a shoe, a last 75 spindle, a carriage in which the spindle is vertically movable, a track on which the carriage can slide lengthwise of the shoe, a lever underlying the spindle, a spring actuating the lever to press the spindle upward, a treadle rod through which said 80 manual means is caused to relieve the closing pressure on the tightening devices, and a connection from the treadle rod to the lever through which the shoe uplifting pressure on the spindle is relieved when the closing pressure on the tightening devices is relieved and is restored when the closing pressure is restored.
19. A machine of the class described having, in combination, means to engage a welt shoe between the welt and upper in position to tighten the upper over the last, and means arranged to present and insert a staple extending transversely across the inseam with one leg on the outer side of the inseam and the other leg on the inner side of the inseam.
20. In a device of the class described for operating on a welted and lasted shoe, contracting means comprising blades for simultaneously engaging from opposite sides in the welt crease at the welt ends and forcing the upper parts toward the medial line of the insole, and staple driving means having

delivery tubes bridging the channel lips and operating adjacent the blades when the upper parts are in contracted position.

21. A machine of the class described having, in combination, upper tightening devices to engage opposite sides of a lasted shoe in the welt crease, carrier levers for swinging said devices inwardly together toward a shoe positioned between them, 10 tackers mounted for movement with said tightening devices laterally of the shoe, and means for holding said devices and the tackers on said carrier levers in different positions of adjustment relatively to each other 15 and longitudinally of the shoe to adapt them for use on different classes of work.
22. A machine of the class described having, in combination, upper tightening de-

vices to engage opposite sides of a welted shoe in the welt crease, means for actuating 20 said devices into upper tightening position, tackers rigidly connected with said upper tightening devices for movement into positions over the shoe welt by the upper tightening devices, and power driven mechanism 25 for said tackers arranged to be set into operation by the workman after he has tightened the upper by the use of said devices.

In testimony whereof I have signed my name to this specification in the presence 30 of two subscribing witnesses.

SAMUEL J. WENTWORTH.
